MEANS FOR CONTROLLING THE WARP IN LOOMS

Filed July 2, 1928

WITNESS

W. Shell.

INVENTOR,
Robert Deleu,

BY
John Seward,
ATTORNEY.

UNITED STATES PATENT OFFICE.

ROBERT DELEU, OF FAIRLAWN, NEW JERSEY.

MEANS FOR CONTROLLING THE WARP IN LOOMS.

Application filed July 2, 1928. Serial No. 289,665.

The object of this invention is to provide means for controlling the warp in a loom in the use of which the goods may be woven so as to avoid the presence of so-called "shiers" or undue spacing of some of the weft threads, or so-called "barre" marks, or too close arrangement of such threads. In ordinary let-off mechanisms a rope is wound one or more times around the beam-head to serve as a brake, and at the rear end of the rope a tension weight is suspended and at the forward end a lighter weight which is adapted to touch the floor or equivalent from time to time as the rope is paid out and so produce a compensating backward slippage of the rope on the beam-head. Due to atmospheric conditions affecting the rope and other causes it is impossible to prevent slippage which is not at times spasmodic, and this gives rise to the said shiers and barre marks. It has been proposed to use, instead of the lighter weight which intermittently touches the floor, a spring to hold the forward end of the rope under tension, and such expedient I find helpful and preferably use. But in the case of the finer quality of goods even this does not entirely remove the fault indicated and hence I have provided for a yielding support for the warp at the point usually assumed by the whip-roll. Such in itself is not broadly new, but it is new to provide the particular yielding substitute for the whip-roll herein set forth. While my improvement is preferably used with that brake-means for the warp-beam in which the rope wound around the beam-head has its rear end tensioned in some way, as by a weight, and its forward end controlled by a spring, as explained, it will be understood that any friction braking means for the beam may be employed.

For my whip-roll substitute I use a bar extending transversely of the warp and around and in contact with which the warp is adapted to extend, said bar being pivoted in the loom frame on an axis transverse of the warp and having its warp-engaged surface convex and curved eccentrically away from said axis in relatively the direction in which the warp extends from the beam, and yielding means normally urging the bar to turn in the direction to press said surface against the warp.

In the drawing,

Fig. 1 is a side elevation of the rear part of a loom embodying the improvement;

Fig. 2 is a side elevation, partly in section

and on a larger scale, of my whip-roll-substitute; and

Fig. 3 is a perspective view of the bar.

In said drawing, 1 is the loom frame which may be substantially of the usual form except for parts added thereto for the support of my whip-roll substitute. 2 is the beam fulcrumed in an adjustable vertical bracket 3. The friction braking means for the beam is here shown as comprising the following parts: 4 is a rope which is wound with one or more turns around the head of the beam 2 in the usual way and 5 is a weighted lever fulcrumed in a stand 6 and connected to the rear end of the rope and acting to tension the warp A. The forward end of the rope is connected to a plunger 6^a arranged to slide vertically in an upstanding bracket 7 which may be secured to the floor and between a suitable abutment 8 on the plunger and the top of the bracket is a spring 9 which the weighted lever 5, acting through the rope, normally tends to maintain in a state of compression.

Constituting in effect a part of the loom frame is a pair of spaced brackets 10 (one at the near side and the other at the far side, Fig. 2) of the warp. In this pair of brackets are pivoted on a horizontal axis the trunnions 11 of a bar 12. This bar is curved transversely of said axis and has a surface 13 which is convex and curved eccentrically away from said axis. The bar is mounted in the brackets 10 so that the eccentricity of its said convex surface 13 shall increase away from said axis in the direction in which the warp extends from the beam. At each end of the bar and near that edge thereof which is remote from said axis it is supported by a cushioning support. Each support consists of a stem 14 which is pivoted on a horizontal axis 15 in an upstanding bracket 16 constituting a part of the loom frame and has a shoulder at 17 and loosely penetrates the bar at 18 and above the bar has a nut 19 screwed thereon to serve as a stop, and interposed between the shoulder 17 and a washer 20 or equivalent at the under side of the bar and coiled on the bolt is a spiral spring 21.

The warp A extends from the beam around the bar 12, and the bar is so positioned that its said convex surface 13 is engaged by the warp and its eccentricity extends away from the axis 13 in relatively the direction in which the warp extends from the beam, as stated above.

The bar is thus adapted to yield as the warp is drawn from the beam and according as the resistance by the beam to its advance varies: if for any reason there should be a sudden change in such resistance the same will be gradually compensated for by the bar, the gradual nature of such compensation being essential in order to prevent the named defects in the fabric and being largely due 10 to the eccentricity of the bar's surface 13.

I claim:

In a loom, the combination, with supporting means and a warp beam journaled therein and braking means for the beam, of a bar 15 extending and pivoted on an axis also ex-

tending transversely of the warp and around and in contact with which bar the warp is adapted to extend, said bar having its warp-engaged surface convex and curved eccentrically away from said axis in relatively the 20 direction in which the warp extends from the beam and a cushioning support upon which the bar rests at a point removed from its said axis, said support being pivoted in said supporting means on an axis parallel with, and 25 being capable of shifting relatively to the bar transversely of, the first-named axis.

In testimony whereof I affix my signature.

ROBERT DELEU.
